UNITED STATES PATENT OFFICE.

CHARLES O. BARNES AND LUCIEN BARNES, SR., OF SYRACUSE, N. Y.

CAR-COUPING.

SPECIFICATION forming part of Letters Patent No. 337,650, dated March 9, 1886.

Application filed November 27, 1885. Serial No. 184,056. (No model.)

To all whom it may concern:

Be it known that we, CHARLES O. BARNES and LUCIEN BARNES, Sr., of Syracuse, in the county of Onondaga, in the State of New York, 5 have invented new and useful Improvements in Car-Couplings, of which the following, taken in connection with the accompanying drawings, is a full, clear, and exact description.

This invention relates to the class of car-couplers in which a swinging head composed of a coupling arm or hook and a supplemental arm formed in one piece is pivoted on the draw-head to swing outward therefrom, and has the supplemental arm standing across the 15 front of the draw-head when the swinging head is in its uncoupled position. A similar swinging head on the draw-head of an approaching car colliding with the aforesaid arm turns the two swinging heads, so as to cause 20 the coupling-arms thereof to interlock with each other.

This invention consists, first, in an improved construction of the swinging head and its seat on the draw-head, whereby said swinging head is carried automatically into its open or uncoupled position. Said automatic action of the swinging head is very essential to this class of couplers, inasmuch as said swinging head must be in its open position in order to 25 interlock with a similar swinging head on the draw-bar of an approaching car, and this can be effected without compelling a person to enter between the cars; and the invention consists, secondly, in the combination, with the 30 swinging head, of a catch arranged compactly and safely in the draw-heads to automatically engage and retain the swinging head in its closed or coupled position, all as herein-after more fully described, and specifically set 35 forth in the claims.

In the accompanying drawings, Figure I is an exterior view of that side of the draw-head at which the swinging head is pivoted. Fig. II is a horizontal section of said draw-head, 40 taken on line $x-x$, Fig. I, and showing it in its coupled position. Fig. III is a side view of our invention with the side of the draw-head broken away to better illustrate the construction of the swinging head and the automatic

catch. Fig. IV is a plan view with the top 50 of the draw-head broken away, showing the swinging head in its uncoupled position. Figs. V and VI are respectively inverted plan and back views of the catch detached, and Fig. VII is an inverted plan view of the swinging head detached.

Similar letters of reference indicate corresponding parts.

A represents the draw-head, formed with the usual recess, R, in its front; and H denotes 60 the swinging head or pivoted coupling-jaw, composed of the coupling hook or arm d' and supplemental arm d , cast in one piece and pivoted on the draw-head to swing outward therefrom in the manner hereinafter explained. 65 This draw-head we form hollow, or with a cavity, c , extending nearly completely across the entire head and partly closed at the front by a wall, a , extending from one side part way across the front of the cavity, and leaving an 70 opening, b , for the passage of the arm d of the swinging head H, which is pivoted on the draw-head at the side which has the opening b . The pivot of the swinging head consists of a pin, e , passing vertically through the same at 75 the junction of its two arms, d and d' , and through coinciding sockets in the upper and lower parts of the draw-head.

The swinging head, which constitutes the coupler proper, has a vertical play on its 80 pivot, and is held normally in an open or uncoupled position by gravity, in conjunction with a beveled face, f , on the under side of the arm d , and a correspondingly-inclined bearing, g , on the draw-head, upon which 85 bearing the arm d rides and thus lifts the swinging head when in its closed or coupled position, as represented in Figs. I, II, and III of the drawings; and so soon as released from the catch, hereinafter described, said swinging head descends and automatically swings out into its open or uncoupled position, as 90 represented in Fig. IV of the drawings.

In order to compel the swinging head to swing out sufficiently to hold the coupling-arm d' out of the way of an approaching similar coupling arm, we provide a second set of inclined bearings, h and h' , on the under side 95

of the swinging head around the pivot thereof and on the adjacent portion of the draw-head.

- Within the cavity *c* of the draw-head, back 5 of the wall *a*, is pivoted a catch or latch, *C*, which reaches with its free end beyond the end of the wall *a* and in the path of the arm *d*, so as to be encountered thereby when the swinging head *H* is thrown into its coupled o position. In this operation the arm *d* throws the catch *C* out of the way and moves past it into the cavity *c* sufficiently to allow the catch to fall forward again and across the front of the end of the arm *d*, as illustrated in Fig. II 5 of the drawings, thereby retaining the swinging head *H* in its coupled position. The catch *C*, resting against the wall *a*, is thereby amply supported to resist the strain transmitted to the catch by the coupled swinging head.
- In order to hold the catch normally in position for retaining the swinging head in its aforesaid position, we provide the draw-head with an inclined bearing, *i*, on the bottom of the cavity *c*, and in position to be traversed 5 by the base of the catch *C* when swung on its pivot, the gravity of the catch causing it to slide down on the bearing *i* and forward against the wall *a*.

- To permit of uncoupling the cars without o entering between them, we connect to the catch *C* a chain, *l*, and pass said chain out through a hole in the top of the draw-head and to an arm, *m*, of a shaft, *n*, which latter is extended across the end of the car, and is 5 provided at opposite sides of the car with cranks by which to turn said shaft, this latter arrangement being common to other car-couplers, and being so simple and well understood that a special illustration thereof is o deemed unnecessary. The draft on the chain *l* has a tendency to lift the catch *C* from its inclined bearing *i* without turning the catch; and to prevent this we provide the draw-head with a second inclined bearing, *o*, which projects from the top plate of the draw-head downward and across the top of the catch, the inclination being such as to crowd the catch *C* back when drawn up against said bearing by the chain *l*.
- The operation of our improved car-coupler is as follows: For coupling the cars the swinging head *H* of at least one of the cars is to be released from the catch *C* to allow said head to swing out into the position shown in Fig. 5 IV of the drawings. This causes the arm *d* to stand across the front of the recess *R* of the draw-head, as shown in Fig. IV of the drawings. In the collision of the draw-heads of the two cars the arm *d*, which stands across the front o of the draw-head, is first encountered by the swinging head of the other draw-head, and is swung back into the cavity *c* and retained by the catch *C*. In swinging into said position the two arms *d* *d'* of the swinging heads of 5 the two cars become interlocked with each other, as illustrated in Fig. II of the drawings,

and in this condition they are retained by the catch *C*. When it is desired to uncouple the cars, the shaft *n* is to be turned to cause the arm *m* thereof to lift the catch *C* by means of 70 the chain *l*, and in lifting the catch it is crowded back by the inclined bearing *o*, so as to release the arm *d* of the swinging head, which latter is then automatically swung out into its open or uncoupled position by the gravity of the 75 swinging head and its inclined bearings *f*, *g*, and *h* thereof.

We are aware that there are now in existence a class of car-couplers in which a latch is pivoted on a rigid draw-head, to engage a 80 suitable hook or catch formed on a similar rigid draw-head of an approaching car, and such latch is made to ride on an inclined or cam-shaped bearing, by which the latch is caused to automatically swing into its closed 85 position for retaining the draw-heads coupled together. Our invention differs materially from such a car-coupler in that we employ the inclined or cam-shaped bearings in combination with a swinging head for automatically 90 throwing the same into its open or uncoupled position.

We are also aware that prior to our present invention car-couplers with pivoted coupling-jaws or swinging coupling-heads have been 95 provided with a longitudinal sliding thrust-bar riding on inclined planes, which automatically carry said bar into engagement with the heel or tail of the coupling-jaw to retain the same in its coupled position; but such car-couplers lack the automatic swinging of the coupling jaw or head into its open or uncoupled position, which is effected by our improved coupler. Furthermore, said prior car-coupler necessitates the longitudinal channeling 100 of the draw-bar for the reception of the thrust-bar, and such channeling has a tendency to weaken the draw-bar.

In our improved car-coupler the catch or latch which retains the pivoted coupling-jaw 110 or swinging head in its coupled position is arranged compactly in the draw-head and the draw-bar is maintained intact.

Having described our invention, what we claim is—

1. The combination of the draw-head provided with the inclined bearing *g*, and the swinging head composed of the coupling-arm *d'* and supplemental arm *d*, and pivoted on the draw-head to swing outward therefrom, 120 and having the arm *d* formed at its under side with the beveled bearing *f*, substantially as described and shown, for the purpose set forth.

2. The combination of the draw-head provided with the inclined bearings *g* and *h'*, and the swinging head *H* composed of the coupling-arm *d'* and supplemental arm *d*, and pivoted on the draw-head to swing outward therefrom, and formed with corresponding inclined bearings, *f* and *h*, substantially in the manner 130 specified and shown, for the purpose set forth.

3. The combination of the draw-head pro-

vided with the cavity *c* and opening *b*, the swinging head *H*, composed of the coupling-arm *d'* and supplemental arm *d*, and pivoted on the draw-head to swing outward therefrom, 5 and having the arm *d* entering the opening *b*, the catch *C*, pivoted in the cavity *c*, inclined bearings *i o*, respectively on the bottom and top of the cavity, and the chain *l*, connected to the catch and passing out from the top of 10 the cavity *c*, substantially as described and shown, for the purpose set forth.

In testimony whereof we have hereunto signed our names and affixed our seals, in the presence of two attesting witnesses, at Syracuse, in the county of Onondaga, in the State 15 of New York, this 7th day of November, 1885.
